(57) **CLAIM**

The ornamental design for an electrical socket, as shown and described.

DESCRIPTION

FIG. 1 is a left, front, top perspective view of an electrical socket showing my new design;
FIG. 2 is a right, rear, bottom perspective view thereof;
FIG. 3 is a front plan view thereof;
FIG. 4 is a rear plan view thereof;
FIG. 5 is a left side elevational view thereof;
FIG. 6 is a right side elevational view thereof;
FIG. 7 is a top elevational view thereof;
FIG. 8 is a bottom elevational view thereof; and,
FIG. 9 is an enlarged view of circled portion 9 in FIG. 1. In the drawings, the broken lines consisting of evenly spaced dash lines depict portions of the electrical socket that form no part of the claimed design. The dot-dash broken lines in the drawings depict the boundaries of the enlarged views and form no part of the claimed design.
